Atty.

UNITED STATES PATENT OFFICE.

HENRY E. HUBBARD, OF CHICAGO, ILLINOIS, ASSIGNOR, BY MESNE ASSIGNMENTS, TO ADDRESSEOGRAPH COMPANY, OF CHICAGO, ILLINOIS, A CORPORATION OF DELAWARE.

PRINTING DEVICE.

Application filed May 5, 1927. Serial No. 188,938.

This invention relates to improvements in printing devices of that class which comprises a plurality of printing forms and an information card carried by a frame and adapted to be stored in accordance with a card index system or stacked in a pile, and run through an addressing or other printing machine for taking an impression from the form. These devices are used not only

10 for printing addresses, but they are now made to print a great deal of additional information, parts of which are liable to change with more or less frequency.

The object of this invention is to provide 15 a printing device comprising a frame having retaining means stamped from the frame and suitably disposed thereon to receive a plurality of printing plates, the retaining means being of such a nature and so disposed upon the frame that they do not weaken the frame for use in the manner intended, but facilitate the insertion and removal of the plates and hold them securely in fixed position on the frame.

20 A further object of the invention is to provide a shiftable index tab which may be used alone or in conjunction with one or more removable index tabs for classifying the printing devices.

25 In the accompanying drawings I have illustrated my invention in a preferred embodiment in which:

Fig. 1 is a front elevation of a printing device embodying the invention, the card being partly broken away.

30 Fig. 2 is a rear elevation of the printing device.

Fig. 3 is a bottom edge view of the printing device.

35 Fig. 4 is a sectional view on the line 4—4 of Fig. 1 omitting the card.

Referring to the drawings, the frame 5 is provided at its top with a bead 6 and at its bottom with a bead 7 on the front thereof,

40 and at its ends with spacing flanges 8 on the back thereof. There are three separate and independent printing plate sections removably mounted on the frame and each bearing type characters, embossed thereon.

45 All of these sections are engaged with and disengaged from the frame by endwise movement and any one of them may be inserted or removed from the frame without

disturbing either of the other sections. The section 9 is held in the frame beneath the 55 bead 7, the lip 12 at one end and the locking device 13 at the other end. This locking device is in the form of a tongue formed by cutting away some of the material of the frame, as best shown in Fig. 2, and it is provided with a stop 13' to engage the end of the plate section 9 opposite the end which is engaged by the lip 12. The plate section 9 has a projection 14 at the end which is engaged by the locking device, and this projection extends upward and is engaged beneath a lip 14' on the frame. This lip 14' holds the plate section 9 in engagement with the bead 7 and so that the top line of type characters thereon will be properly spaced 70 with relation to the bottom line of type characters on the middle plate section 10. It is desired to avoid the provision of a lip to engage the top edge of the plate section 9 between the ends thereof, to facilitate insertion and removal of the plate, and in order to provide the lip 14' at the end of the plate and because of the size of the locking device 13, it is necessary to provide the projection 14 and to locate the lip 14' opposite the end of the plate section 10 which is 75 cut away at 15 to accommodate the projection 14 and the lip 14'.

The middle plate section 10 is held on the frame beneath the lip 16 at one end, the 85 lips 17 engaging the top edge of the plate section, the lip 18 engaging the bottom edge at one corner and the locking device 19 having a stop 19' thereon to engage the opposite end. The lip 16' is located above the locking device 13 and the locking device 19 is located above the lip 12 so that the two plate sections 9 and 10 are inserted in and removed from the frame at opposite ends of the frame. The lip 18 is located below the locking device 19 at the corner of the plate section 10.

Only one lip is provided to engage the upper edge of the lower plate section 9, at the projection 14, because it will hold the right 100 end of the plate section 9 in engagement with the bead 7, and the lip 18 will prevent the left end of this plate section from becoming disengaged from the bead, Fig. 1. Only one lip 18 engages the lower edge of 105 the middle plate section 10 because the lip

14' engaging the right end of the plate section 10, Fig. 1, will prevent the section from becoming disengaged from the lips 17.

The printing plate section 11 is held between the lip 20 at one end and the locking device 21 having a stop 22 at its other end, and beneath lips 23 which engage the bottom edge of the plate and lips 24 which engage the top edge of the plate. The lip 20 is located above the locking device 19 and the lip 12 and the locking device 21 are located above the lip 16 and the locking device 13 so that the section 11 is adapted to be inserted in and removed from the frame at the same end as the lower section 9. The lips and the locking devices are all stamped up from the frame and the locking devices 19 and 21 are made like the locking device 13.

A tab 25 having two arms 26, 26' is pivoted at 27 to the upper portion of the frame adjacent one end thereof and the arms are so disposed that by shifting the tab one may be projected above the top edge of the frame and the other swung to a position at the back of the frame and below the top edge thereof. This shiftable tab has a finger 28 which projects through a slot 29 in the frame and engages one or more stops 30 to hold the shiftable tab in adjusted position. Alongside the shiftable tab the frame is provided with keepers 31 to receive removable tabs 32, these removable tabs being used in conjunction with the shiftable tab for classifying the printing devices according to a card index or other classification system. The tab subject matter is not claimed herein but forms the subject of my divisional application Serial No. 252,158, filed February 6, 1928.

The card 33 is removably engaged with the bead 6, the corner lip 34, and the bottom lips 35, 35', the latter being arranged to engage the bottom edge of the card at the end opposite the corner which is engaged by the corner lip 34. A stop 36 on the frame engages the right end of the card and holds it in place in the frame with its left end engaged with the corner stop 34, Fig. 1. The card bears printed matter relating to the printing device and it may be an impression from some or all of the plates, or other information data and the card is insertable in and removable from the frame in a manner similar to the printing plate sections.

My invention provides a frame and plate section construction which has been found to be highly desirable in special classes of work, the plates can be easily inserted in and removed from the frame, they are held in substantially fixed position in the frame in proper spacing relation to each other, and the retaining means are disposed on the frame in a manner which will permit the plates to be easily inserted and removed and which will hold the plates in proper position on the frame and which do not weaken the

frame for the purposes for which it is intended. The shiftable tab is a convenient means for temporarily sub-classifying a printing device without completely disturbing its position in a more or less complicated classification and it can be easily operated for this purpose.

This invention presents improvements upon Patents No. 1,375,683 patented April 26, 1921 and No. 1,310,026 patented September 6, 1921, which have been found to be desirable in actual use, and while I intend and prefer that the devices shall be made, as they have been made, as illustrated in the drawings and herein described, I reserve the right to make such changes in the form, construction and arrangement of parts as come within the scope of the following claims.

I claim:

1. A printing device of the character described comprising a frame, and three separate printing plate sections removably secured in place thereon one above the other, said frame having retaining means stamped therefrom to engage and hold the plate sections, and said means comprising a locking device for each plate section to engage an end thereof, said locking devices being disposed alternately at the ends of the frame to engage one end of the middle section and the opposite ends of the top and bottom sections.

2. A printing device of the character described comprising a frame, and three separate printing plate sections removably secured in place thereon one above the other and spaced from each other, said frame having retaining means stamped therefrom to engage and hold the plate sections, and said means comprising a yieldable locking device for each plate section to engage an end thereof, said locking devices being disposed alternately at the ends of the frame to engage one end of the middle section and the opposite ends of the top and bottom sections, whereby the middle section is insertable in and removable from the frame over its locking device at one end of the frame and the top and bottom sections are insertable in and removable from the frame over the locking devices at the other end of the frame.

3. A printing device of the character described comprising a frame, and two separate printing plate sections removably secured in place thereon one above the other, said frame having retaining means stamped therefrom to engage and hold the plate sections, and said means comprising a locking device to engage one end of the lower plate section and a lip to engage the corresponding end of the upper plate section, the lower plate section having a projection from its upper edge at said end and the upper plate section being cut away at its lower edge at said end to accommodate said pro-

jection, and a lip on the frame opposite said cutaway portion of the upper plate section to engage the projection on the lower plate section.

- 5 4. A printing device of the character described comprising a frame and three separate printing plate sections removably secured in place thereon, one above the other, said frame having retaining means stamped 10 therefrom to engage and hold the plate sections, and said means comprising a bead at the lower edge of the frame to engage the lower edge of the bottom section, an end lip at one end of the frame and a locking device at the other end of the frame to engage the ends of said bottom section, a projection on the upper edge at one end of said bottom section and a lip on the frame to en- 15 gage said projection, an end lip and a locking device to engage the ends of the middle plate section, a lip to engage the bottom edge of the middle plate section at the end thereof which is engaged by the locking device, and lips to engage the top edge of the middle plate section, an end lip and a locking device to engage the ends of the top plate section, lips to engage the top edge of the bottom edge of the top plate section, the locking device for the middle plate section being located between the end lips for the 20 top and bottom plate sections and the end lip for the middle plate section being located between the locking devices for the top and bottom plate sections. 25

HENRY E. HUBBARD.
